ELECTRICAL CONNECTION MEANS

Harry A. Douglas, Bronson, Mich., assignor to
Kingston Products Corporation, a corporation
of Indiana

Application May 31, 1935, Serial No. 24,250

29 Claims. (CL. 173—328)

My invention relates to electrical connection means, particularly to connection means which may involve a plurality of conductor terminal receiving means mounted on a common support, and, more particularly to a construction in which a plurality of conductor terminal receiving means constituting a plurality of terminal posts are integrally formed, and the principal object of my invention is to provide new and improved electrical connection means. In the drawing accompanying this specification and forming a part of this application I have shown, for purposes of illustration, several forms which my invention may assume. In this drawing:

15 Figure 1 is a side elevation, partly in fragmentary vertical section, of one embodiment of my invention, this embodiment itself embodying several fundamental embodiments.

Figure 2 is a fragmentary enlarged view of the embodiment of Figure 1, partly in longitudinal vertical section.

Figure 3 is a horizontal sectional view taken on the line 3—3 of Figure 2, looking in the direction of the arrows.

25 Figure 4 is a vertical cross-sectional view taken on the line 4—4 of Figure 2, looking in the direction of the arrows, a conductor terminal being added in Figure 4.

Figure 5 is a vertical cross-sectional view taken 30 on the line 5—5 of Figure 2, looking in the direction of the arrows, and

Figure 6 is a horizontal section taken on the line 6—6 of Figure 2, looking in the direction of the arrows.

35 Referring to Figure 1, there is here shown an electrical connection means comprising a plurality of conductor terminal receiving means or terminal posts, there being in this instance eight terminal posts, 10, 11, 12, 13, 14, 15, 16, 17, mounted on a common composite support or base 18. The construction of the embodiment of Figure 1 will be clearly understood, first, by a consideration of the construction of two of the terminal posts, 13, 14.

45 Each terminal post 13, 14 comprises a housing 19, 20, the housing 19 being integral with the housing 20. The housing of each terminal post 13, 14 includes a tubular body portion of generally oblong rectangular cross-section, as may be seen 50 in Figure 6.

The tubular body portion of the terminal post 13 has opposite walls 21, 22 integrally joined at their tops by a loop 23 forming an aperture 24. The tubular body portion of the terminal post 14 55 has opposite walls 25, 26, integrally joined at

their tops by a loop 27 forming an aperture 28. The adjacent walls 22, 25 of the posts 13, 14 are extended downwardly, below the level of the lower ends of the walls 21, 26, by an amount here shown as approximately equal to the thickness 5 of the metal of the walls, and these extended walls 22, 25 are integrally joined at their lower ends by a bridge portion 29 extending at right angles to the walls 22, 25.

The tubular body portion of the post 13 also 10 has opposite walls 30, 31 at right angles to the walls 21, 22. The wall 30 is made in halves, one half 32 being integral with the wall 21, and the other half 33 being integral with the wall 22. The wall 31 is made in halves, one half 34 being 15 integral with the wall 21, and the other half 35 being integral with the wall 22. In like manner the post 14 also has opposite walls 36, 37, at right angles to the walls 25, 26, and each of these walls 36, 37 is made in halves 38, 39 and 20 40, 41, the halves 38, 40 being integral with the wall 25 and the halves 39, 41 being integral with the wall 26. The two part walls 30, 31 of the post 13 and the two part walls 36, 37 of the post 14 may have their upper ends 42, 43 and 44, 45 25 of arcuate form, to form the lower margins of the apertures 24, 28 of the loops 23, 27.

The posts 13, 14 are provided with feet, two of which 46, 47 are shown as provided on the post 13, these feet 46, 47, being formed by extensions 30 of the wall halves 32, 34, bent outwardly at right angles to the wall halves 32, 34. Two of the feet 48, 49, are provided on the post 14, being formed by extensions of the wall halves 39, 41, bent outwardly at right angles to the wall halves 35 39, 41. Two more feet 50, 51 may be provided, these being formed by lateral extensions of the bridge 29, and the feet 50, 51 are thus common to the posts 13, 14.

The bottoms of the feet 46, 47 of the post 13, 40 and of the feet 48, 49 of the post 14, and of the feet 50, 51 on the bridge 29, and the bottom of the bridge 29 itself, are all in a common plane, and adapted to abut to a plate 52 here shown as of insulating material. The posts 13, 14 may be 45 held to the plate 52 in a manner which will appear.

The wall 36 of the post 14 is provided with an ovate aperture 53, formed by recessing the abutting edges of the walls 38, 39; and the wall 37 50 is provided with an ovate aperture 54, formed by recessing the abutting edges of the walls 40, 41, the apertures 53, 54 having a common axis.

Detent means 55, slidably positioned in the tubular body of the terminal post 14, is provided 55

for cooperation with the aperture 28 and a conductor terminal insertable therein. The detent means 55 has a body portion generally of U-shape, the bight 56 of the U being, in this instance, arch-shaped. The U-shaped detent means 55 has legs 57, 58 with which the arch-shaped bight 56 merges. The inner periphery of the bight 56 of the detent means 55 is in general registry with the upper portion of the apertures 53, 54. The 10 arch-shaped bight 56 of the detent means 55 is provided at its top with a protuberance 59, which in this instance is of approximately semi-cylindrical form, struck up from the bight 56, the axis of the protuberance 59 being at right angles to the 15 axis of the arch 56 and at right angles to the axis of the aperture 28. The protuberance 59 is normally above the arcuate margins 44, 45. The upward movement of the detent means 55 is limited by shoulders 60, 61 extending inwardly from 20 near the upper ends of the walls 25, 26, somewhat below the junctions of the walls 25, 26 with the loop 27. The detent means 55 is provided with 25 projections 62, 63 extending outwardly from the sides of the arch 56, the upper ends of these 25 projections 62, 63 being adapted to abut the shoulders 60, 61. The projections 62, 63 may be struck out from the arch 56.

Detent means 64, slidably positioned in the tubular body of the post 14, below the detent 30 means 55, is provided for cooperation with the apertures 53, 54, and with the aperture formed by the detent means 55, and with a conductor terminal insertable through these apertures. The detent means 64 is generally of U-shape, 35 the bight 65 of the U being, in this instance, flat and joined to legs 66, 67. The bight 65 is provided with an upwardly extending protuberance 68, which in this instance is of approximately semi-cylindrical form, struck up from the bight 40 65. The protuberance 68 normally extends above the lower arcuate margins of the apertures 53, 54, and has its axis at right angles to the axis of the apertures 53, 54.

The plate 52 serves also as an abutment for a 45 spring 69, disposed within the tubular body of the terminal post 14, the other end of the spring engaging the inside surface of the bight 65 of the detent means 64, thereby biasing the detent means 64 against the lower ends of the legs 57, 58 of the detent means 55 and biasing the detent means 55 against the shoulders 60, 61.

A detent means 70, slidably positioned in the tubular body of the post 13, is cooperable with the aperture 24 and a conductor terminal insertable therein. The detent means 70 is, in this 55 instance, identical with the detent means 64 except that it cooperates with the aperture 24 formed by the loop 23 instead of cooperating with apertures 53, 54, as does the detent means 64.

The plate 62 serves also as an abutment for one end of a spring 71, the other end of the spring engaging the inside surface of the bight of the detent means 70. The spring 71 biases the detent means 70 upwardly against shoulders 72, 73 extending inwardly at approximately the tops of the walls 21, 22. These shoulders 72, 73 are similar to the shoulders 60, 61 of the post 14, except that they are closer to the junctions 75 between the walls 21, 22 and the loop 23 than are the shoulders 60, 61 to the junction between the walls 25, 26 and the loop 27.

In addition to the plate 62 the base 18 includes also an insulating plate 74 provided with apertures 75, 76, which desirably snugly fit the body

portions of the terminal posts 13, 14 and through which these terminal posts are insertable. The terminal posts 13, 14 being spaced, and hence also the apertures 75, 76, the insulating plate 74 provides an intermediate portion 77 overlying the bridge 29 and disposed between the walls 22 and 25. The insulating plate 74 also overlies the feet 46, 47, 48, 49, 50, 51. If desired a spacer 78 may be provided between the plates 52, 74, of approximately the thickness of the 10 before-mentioned feet, the spacer being provided with an aperture 79, generally outlining the feet of such terminal posts as may be mounted on the base. The parts of the composite base 18 may be held together by a metallic channel 80, having flanges 81, in which the plates 52, 74, and the spacer 78, if used, are disposed, the flanges 81 of the channel 80 being provided with fingers 82 clinched over the top of the insulating plate 74, to firmly hold in place the terminal 20 posts 13, 14 or any other similar posts.

In Figure 4 is shown a conductor terminal 83 in cooperative relation to the aperture 28 of the terminal post 14. The protuberance 59 of the detent means 55 is in engagement with an annular furrow 84, formed in a cylindrical part of the conductor terminal 83. The conductor terminal is provided with a frustro-conical end 85, which serves to cam the detent means 55 downwardly against the bias of the spring 69, as 30 the conductor terminal 83 is being inserted into the aperture 28, further inserting movement causing the protuberance 59 to snap into the furrow 84. The conductor terminal 83 may be fastened to the conductor disposed therein by 35 swedging, as indicated by the wedge indentations 86.

It will be noted that when a conductor terminal 83 is connected to the terminal post 14, through the aperture 28, as shown in Figure 4, 40 the upper inside surface of the bight 65 of the detent means 55 is somewhat below the upper margins of the apertures 53, 54, the detent means 55 having been moved downwardly somewhat from its position shown in Figure 2, by 45 insertion of the conductor terminal 83. Also, the detent means 55 has moved the detent means 64 downwardly a small amount, the protuberance 68 being however still above the lower margins of the apertures 53, 54. In this position of the parts the lower ends of the legs 57, 58 of the detent means 55 are still in abutment with the top of the bight 65 of the detent means 64.

If another conductor terminal such as 83 now 55 is inserted through the apertures 53, 54, the upper portion of the body of the conductor terminal will slide along the inside surface of the bight 56 of the detent means 55, and the protuberance 68 will snap into the furrow, such as 60 84, of the conductor terminal. Thus the spring 69 biases the protuberance 68 against the lower conductor terminal 83, in turn biasing the lower conductor terminal against the underside of the bight of the detent means 55, thereby biasing the 65 upper conductor terminal 83 against the upper inside surface of the aperture 28. In this position of the parts the lower ends of the legs 57, 58 of the detent means 55 are no longer in contact with the upper surface of the bight 65 70 of the detent means 64.

It will be obvious that the conductor terminal 83 may be removed from the aperture 28 and inserted in the lower unoccupied terminal receiving apertures 53, 54 and held there by the 75

protuberance 88. Thus the terminal post 14 is adapted to receive and hold a conductor terminal in either of its terminal receiving apertures 28 and 53, 54, or in both the aperture 28 and the 5 apertures 53, 54, equally well.

The terminal post 13 is adapted to receive and hold a single conductor terminal 83 in a manner which will be obvious from the foregoing.

It is evident that the terminal posts 13, 14 are 10 adapted to interconnect conductor terminals up to a maximum of three.

It will be apparent from the described construction of the terminal posts 13, 14 that the 15 housings of these posts may be made of a single piece of sheet metal, the walls of the post 13 being formed as hereinbefore described and the channel-shaped halves of the body portion being moved toward each other while bending the loop 23 until the longitudinal edges of the halves of 20 the body portion form the lines or planes of registry 81, 88, where the wall halves 32, 33 and the wall halves 34, 35 abut each other. In like manner, the terminal post 14 may be formed to the shape described by moving the channel-shaped halves of the body portion toward each other to bend the loop 27 until the longitudinal edges of the wall halves 38, 39 and 40, 41 form the lines or planes of registry 89, 90. The integrally connected walls 22, 25 are also bent 25 so as to form the bridge portion 29. The detent means 55, 64 and the spring 69 may be assembled with the terminal post 14 and the detent means 70 and the spring 71 with the terminal post 13 by simply inserting them in the tubular portion 30 of the terminal posts to assume the positions hereinbefore described, whereupon the terminal posts may be assembled with the base 18.

The base 18 also mounts a pair of posts 10, 11, each of the posts being identical with the post 13. 40 The posts 10, 11 are integrally joined by a bridge portion 99, similar to the bridge portion 29 joining the posts 13, 14. Each post 10, 11 is also provided with a single detent means, similar to the detent means 70 of the post 13, and operable in 45 the same manner. The compound post comprising the posts 10, 11 is also provided with feet as described in connection with the posts 13, 14 and a view of the posts 10, 11, similar to the view of the posts 13, 14 in Figure 3 appears identical with that view. The compound post 10, 11 is obviously adapted for interconnecting a maximum of two conductor terminals such as 83.

The base 18 also mounts a compound post comprising terminal posts 16, 17, each of which 55 is identical with the post 14. The posts 16, 17 are integrally joined by a bridge portion 100. Each post 16, 17 is provided with two detent means, similar to the detent means 55, 64 of the post 14 and operable in the same manner. The 60 compound post 16, 17 is also provided with feet as described in connection with the compound post 13, 14 and a view of the posts 16, 17, similar to the view of the posts 13, 14 in Figure 3 appears identical with that view. The compound post 16, 17 is obviously adapted for interconnecting a maximum of four conductor terminals such as 83.

The base 18 also mounts a post 12, adapted to interconnect a maximum of two conductor terminals such as 83. The post 12 is identical with the post 14 except that it is not connected by a bridge portion such as 29 to an adjacent post and is, moreover, provided with four feet 101, 102, 103, 104, as may be seen in Figure 3. The feet 70 75 101, 102 are formed by extensions of wall halves,

corresponding to the wall halves 38, 39 of the post 14, bent outwardly at right angles from the wall halves, and the feet 103, 104 are similarly formed by extensions of wall halves, corresponding to the wall halves 40, 41 of the post 14, bent 5 outwardly at right angles from the wall halves.

The base 18 also mounts a post 15, adapted to receive a single conductor terminal, such as 83. The post 15 is identical with the post 13 except that it is not connected by a bridge portion, 10 such as 29, to an adjacent post and, moreover, is provided with four feet 105, 106, 107, 108, in a manner analogous to that already described in connection with the post 12.

Both the post 12 and the post 15 may have 15 conductor means (not shown) other than a conductor terminal such as 83, connected thereto.

It will be evident that the housings of the posts 12, 15 and also of the compound posts 10, 11 and 16, 17 may each be made of a single piece of sheet 20 metal, analogously as has been described in connection with the posts 13, 14. Moreover, any desired combination as regards the number of integrally connected terminal posts and the number of terminal receiving apertures provided by 25 the respective terminal posts may be made up in a continuous integral series. On the other hand, connection blocks or strips may be made up of various combinations of compound posts or single posts or both.

30

All of the posts 10 through 17 are held in abutment with the plate 52 of the base by the apertured plate 74, as already described in connection with the posts 13, 14, apertures in the plate 74, similar to the apertures 75, 76, being of course 35 also provided for the posts 10, 11, 12, 15, 16, 17. Plates such as 74 may be cut in any desired length from stock, previously provided, if desired, with apertures such as 75, 76 and so on. These apertures may all be of the same size and shape and 40 equally spaced so that besides being adapted to receive single terminal posts, any standard compound post, according to the present disclosure, may be received therethrough.

The base 18 may be mounted on a support as 45 by, for example, fastening means passing through apertures 109, 110 in the base.

From the foregoing it will be apparent to those skilled in the art that the illustrated embodiments of my invention provide new and improved 50 electrical connection means, readily and conveniently constructed and assembled, and accordingly accomplish at least the principal object of my invention. On the other hand, it also will be obvious to those skilled in the art that the 55 illustrated embodiments of my invention may be variously changed and modified, or features thereof, singly or collectively, embodied in combinations other than those illustrated, without departing from the spirit of my invention or 60 sacrificing all of the advantages thereof, and that accordingly, the disclosure herein is illustrative only, and my invention is not limited thereto.

I claim:

1. A plurality of conductor terminal receiving 65 means including an undulating wall made from sheet metal stock, said wall comprising a plurality of undulations, each undulation forming at least two spaced walls of one of said conductor terminal receiving means, each terminal receiving means having a predetermined number of detent means, and each having resilient means for biasing said detent means into cooperative relation with conductor terminals, the amplitude of any given one of said undulations being de- 70 75 75

- pendent upon the predetermined maximum number of detent means of that conductor terminal receiving means of which said given undulation forms a part.
5. 2. A plurality of conductor terminal receiving means including an undulating wall made from sheet metal stock, said wall comprising a plurality of undulations, each undulation forming at least two spaced relatively fixed walls of one of said conductor terminal receiving means, each terminal receiving means being so constructed and arranged that it is adapted to receive a predetermined maximum number of conductor terminals, the amplitude of any given one of said undulations being dependent upon the predetermined maximum number of conductor terminals that said conductor terminal receiving means, of which said given undulation forms a part, is adapted to receive.
10. 3. A plurality of conductor terminal receiving means including an undulating element made from sheet metal stock, said element comprising a plurality of undulations continuous with each other from the crest of one to the crest of the adjacent one in the direction of progression of said undulations, each undulation forming at least two spaced relatively fixed walls of one of said conductor terminal receiving means, each terminal receiving means having a predetermined number of conductor terminal receiving apertures, the amplitude of any given one of said undulations being dependent upon the number of conductor terminal receiving apertures provided in that conductor terminal receiving means of which said given undulation forms a part.
15. 4. A plurality of conductor terminal receiving means, each having a body portion, the longitudinal axes of said body portions extending approximately parallel to each other and being disposed in a common general plane, adjacent body portions each having a side spaced from and facing a side of the adjacent body portion, each said side being defined by a continuous wall extending transversely across said general common plane, each of said body portions providing at least one conductor terminal receiving aperture extending transversely of the longitudinal axis of the respective body portion; and connecting means for mechanically and electrically integrally connecting said sides; said connecting means and said body portions being formed integrally from sheet metal stock.
20. 5. A plurality of conductor terminal receiving means, each having a body portion, a plurality of said body portions having a tubular cross-section, the axes of said tubular body portions extending approximately parallel to each other and being disposed in a common general plane, adjacent body portions each having a side spaced from and facing a side of the adjacent body portion, each said side being defined by a continuous wall extending transversely across said general common plane, each of said body portions providing at least one conductor terminal receiving aperture extending transversely of the longitudinal axis of the respective body portion; and connecting means for mechanically and electrically integrally connecting said sides; said connecting means and said body portions being formed integrally from sheet metal stock.
25. 6. In combination: a composite base including superimposed preformed insulating portions; at least two conductor terminal receiving means mounted on said base and extending laterally therefrom; said terminal receiving means each
- having detent means constructed and arranged for movement in said lateral direction, and each having resilient means for biasing said detent means into cooperative relation with conductor terminals receivable in said terminal receiving means; each of said resilient means abutting the same one of said insulating portions; and connecting means for mechanically and electrically integrally connecting said two conductor terminal receiving means; said connecting means being disposed between said insulating portions of said base.
7. In combination: a composite base including superimposed preformed insulating portions, one of said portions having spaced apertures; at least two conductor terminal receiving means mounted on said base, having body portions disposed through said apertures; said terminal receiving means each having detent means constructed and arranged for movement longitudinally of said body portions, and each having resilient means for biasing said detent means into cooperative relation with conductor terminals receivable in said terminal receiving means, each of said resilient means abutting the same one of said insulating portions; and connecting means for mechanically and electrically integrally connecting said two conductor terminal receiving means; said connecting means being disposed between said insulating portions of said base.
8. A plurality of conductor terminal receiving means including an undulating wall made from sheet metal stock, said wall comprising a plurality of undulations, each undulation forming at least two spaced relatively fixed walls of one of said conductor terminal receiving means, each terminal receiving means being so constructed and arranged that it is adapted to receive a predetermined maximum number of conductor terminals, each terminal receiving means having a predetermined number of detent means, and each having resilient means for biasing said detent means into cooperative relation with conductor terminals, the amplitude of any given one of said undulations being dependent upon the predetermined maximum number of conductor terminals that said conductor terminal receiving means, of which said given undulation forms a part, is adapted to receive.
9. A plurality of conductor terminal receiving means, each having a body portion, the longitudinal axes of said body portions defining a plane, adjacent body portions having adjacent walls spaced from each other laterally, said body portions providing apertures for receiving conductor terminals, at least one of said body portions providing at least two said apertures, the axes of said at least two apertures being spaced from each other in the direction of the longitudinal axis of said at least one body portion and defining a plane transverse to said first named plane; detent means, for each terminal receiving means, constructed and arranged for cooperation with said apertures and conductor terminals receivable therein; resilient biasing means, for each terminal receiving means, constructed and arranged to bias said detent means into cooperative relation with the conductor terminals; and connecting means for mechanically and electrically integrally connecting said adjacent walls; said connecting means and said body portions being formed integrally from sheet metal stock.
10. In combination: a composite base including superimposed preformed insulating portions;

at least two conductor terminal receiving means, having tubular body portions, mounted on and extending laterally from said base, at least the base-ends of said tubular body portions being 5 open; and connecting means for mechanically and electrically integrally connecting said two conductor terminal receiving means; said tubular body portions and said connecting means being formed from a single sheet metal stamping; 10 and said connecting means being disposed between said insulating portions of said base and one of said portions closing said open ends of said tubular body portions.

11. In combination: a composite base including 15 superimposed preformed insulating portions, one of said portions having spaced apertures; at least two conductor terminal receiving means mounted on said base, having tubular body portions disposed through said apertures, at least 20 the base-ends of said tubular body portions being open; and connecting means for mechanically and electrically integrally connecting said two conductor terminal receiving means at one end thereof; said tubular body portions and said 25 connecting means being formed from a single sheet metal stamping; said connecting means being disposed between said insulating portions of said base and one of said portions closing said open ends of said tubular body portions; said 30 tubular body portions and said connecting means and said apertures being so constructed and arranged that said tubular portions are freely insertable through said apertures without distortion of said terminal receiving means.

35 12. In combination: a base; a plurality of spaced conductor terminal receiving means mounted on said base, at least one of said receiving means having a tubular body portion formed by juxtaposed channel shaped parts, the free edges of the sides of said channel shaped 40 parts defining a plane transverse to the direction of spacing of said terminal receiving means, each receiving means providing at least one conductor terminal receiving aperture; said tubular body portion having a bent sheet metal loop at its free end providing one of said terminal receiving apertures; and connecting means for mechanically and electrically integrally connecting said plurality of terminal receiving means; 45 said connecting means and said body portions and said loop being formed integrally from a single sheet metal stamping.

13. A plurality of conductor terminal receiving means including a common portion made 55 from an elongated sheet metal element, said common portion comprising a plurality of undulations, said element being so constructed and arranged that each undulation forms the walls of one of said conductor terminal receiving means having a tubular body portion, each terminal receiving means having a predetermined number of detent means, and each having resilient means for biasing said detent means into cooperative relation with conductor terminals, the 60 amplitude of any given one of said undulations being dependent upon the predetermined maximum number of detent means of that conductor terminal receiving means of which said given undulation forms a part.

70 14. A plurality of conductor terminal receiving means including a common portion made from an elongated sheet metal element, said common portion comprising a plurality of undulations, said element being so constructed and arranged 75 that each undulation forms the relatively fixed

walls of one of said conductor terminal receiving means having a tubular body portion, each terminal receiving means being so constructed and arranged that it is adapted to receive a predetermined maximum number of conductor terminals, the amplitude of any given one of said undulations being dependent upon the predetermined maximum number of conductor terminals that said conductor terminal receiving means, of which said given undulation forms a part, is adapted to receive. 5

15. A plurality of conductor terminal receiving means including a common portion made from an elongated sheet metal element, said common portion comprising a plurality of undulations, 15 said element being so constructed and arranged that each undulation forms the relatively fixed walls of one of said conductor terminal receiving means having a tubular portion, each terminal receiving means being so constructed and arranged that it is adapted to receive a predetermined maximum number of conductor terminals, 20 each terminal receiving means having a predetermined number of detent means, and each having resilient means for biasing said detent means into 25 cooperative relation with conductor terminals, the amplitude of any given one of said undulations being dependent upon the predetermined maximum number of conductor terminals that said conductor terminal receiving means, of which 30 said given undulation forms a part, is adapted to receive.

16. In combination: an insulating base having an aperture; terminal means having an open ended tubular portion extending into said aperture, said terminal means having a transverse aperture for receiving an electrical conductor terminal; detent means, disposed within said tubular portion, for cooperation with said transverse aperture and the electrical conductor terminal; resilient means, disposed within said tubular portion for biasing said detent means into 40 cooperating position; a plate engaging said resilient means and extending over said open end of said tubular portion; and means for holding said plate against said base. 45

17. An electrical conductor terminal receiving means, comprising: detent means, formed of sheet metal, having a body of generally U-shape, the bight of said body having a generally semi-cylindrical extension having its axis at right angles to the axis of said bight, said extension extending in a direction away from the outer surface of said bight of said detent means and being constructed and arranged for cooperation with 55 a conductor terminal extending parallel to the axis of said bight; means for supporting said detent means for movement relatively to said supporting means; and resilient means for biasing said detent means in said direction into cooperating position. 60

18. An electrical conductor terminal receiving means, comprising: first detent means, formed of sheet metal, having a body of generally U-shape, the bight of said body having a generally semi-cylindrical extension having its axis at right angles to the axis of said bight, said extension of said detent means being constructed and arranged for cooperation with a conductor terminal; second detent means constructed and arranged for cooperation with a conductor terminal insertable in the bight of the body of said first detent means; means for supporting said first and second detent means for movement relatively to said supporting means; and resilient means 65 70 75

for biasing said first and second detent means into cooperating position with the conductor terminals.

19. In combination: a base having an aperture; an electrical conductor terminal receiving means having a free end and a supported end and comprising a tubular body formed of sheet metal, said tubular body including two juxtaposed channel shaped parts; said aperture and said tubular body being relatively so constructed and arranged that said tubular body is insertable free end first through said aperture; said terminal receiving means having a plug conductor terminal receiving aperture extending in a direction transverse to the axis of said tubular body; detent means, disposed in said tubular body, constructed and arranged to cooperate with said aperture and a plug conductor terminal receivable in said aperture; resilient means for biasing said detent means to cooperating position; and means for mounting said receiving means on said base including sheet metal portions integral with said tubular body, said portions being preformed to overlie a portion of said base thereby to limit such insertion of said tubular body through said aperture.

20. An electrical conductor terminal receiving means, comprising: loop means, bent from sheet metal stock, providing an aperture for receiving a conductor terminal; two juxtaposed channel shaped parts forming a split tubular body; said tubular body having an aperture for receiving a conductor terminal; said loop means and said channel shaped parts being formed integrally from a single sheet metal stamping; and means for holding a conductor terminal in either or both of said apertures.

21. An electrical conductor terminal receiving means, comprising: loop means, bent from sheet metal stock, providing an aperture for receiving a conductor terminal; two juxtaposed channel shaped parts forming a tubular body having a split in its walls; said tubular body having an aperture, intersecting said split, for receiving a conductor terminal; said loop means and said channel shaped parts being formed integrally from a single sheet metal stamping; and means for holding a conductor terminal in either or both of said apertures.

22. An electrical conductor terminal receiving means cooperable with a plurality of conductor terminals, comprising: detent means, including a plurality of detents, constructed and arranged to cooperate with the conductor terminals; at least one of said detents having a generally U-shaped body formed of sheet metal; and means for movably supporting said detent means; said supporting means having an aperture a margin of which registers approximately with the surface defining the inside of the bight of said U-shaped sheet metal body thereby to leave said aperture and said bight free for the insertion of one of the conductor terminals through said aperture and within said inside surface; another of said detents being so constructed and arranged that it is cooperable with said bight and the conductor terminal inserted therein and that movement of said last named detent toward said bight is limited by engagement of said last named detent with the ends of the legs of said U-shaped sheet metal body; and means biasing said last named detent to said limiting position.

23. In combination: a base having an aperture; terminal means having an open ended tubular portion extending into said aperture, said ter-

inal means having a transverse aperture for receiving an electrical conductor terminal; detent means, disposed within said tubular portion, for cooperation with said transverse aperture and the electrical conductor terminal received therein; resilient means disposed within said tubular portion, for biasing said detent means into cooperating position; said tubular portion at its open end having parts preformed so that they extend laterally outwardly and overlie a portion of said base; said aperture and said terminal means being relatively so constructed and arranged that said terminal means is insertable through said aperture and that inserting movement is stopped by said laterally extending parts; a plate engaging said resilient means and extending over said open end of said tubular portion and over said laterally extending parts; and means for holding said plate against said base.

24. In combination: an insulating base having an aperture; terminal means having an open ended tubular portion extending into said aperture, said terminal means having a transverse aperture for receiving an electrical conductor terminal; detent means, disposed within said tubular portion, for cooperation with said transverse aperture and the electrical conductor terminal received therein; resilient means, disposed within said tubular portion for biasing said detent means into cooperating position; an insulating member engaging said resilient means and extending over said open end of said tubular portion; and means for holding said insulating member in position, said holding means including a metallic channel in which said insulating member and said insulating base are disposed, side portions of said channel being bent around said base.

25. An electrical conductor terminal receiving means, comprising: detent means, of generally U-shape, formed of sheet metal; resilient means for biasing said detent means into cooperating position with a conductor terminal; means for supporting said detent means for movement, in the general direction of the longitudinal axis of said U-shape, relatively to said supporting means; said supporting means including a wall adjacent the outside lateral surface of a leg of said U-shaped detent means, said wall having a part bent into the general plane of said leg; and means, cooperable with said part of said wall, including a portion struck out from said sheet metal detent means, constructed and arranged so that movement of said detent means in said direction toward said cooperating position is limited by engagement of said struck-out portion with said part of said wall.

26. An electrical conductor terminal receiving means, comprising: detent means, having a portion of generally U-shape, formed of sheet metal, so constructed and arranged that an outside part of the bight of said U-shaped portion is cooperable with a conductor terminal; resilient means for biasing said detent means into cooperating position with the conductor terminal; means for supporting said detent means for movement relatively to said supporting means; said supporting means including a wall adjacent the outside lateral surface of a leg of said U-shaped detent means, said wall having a part bent into the general plane of said leg; and means cooperable with said part of said wall, including a portion struck out from said sheet metal detent means, constructed and arranged so that movement of said detent means in the

direction in which said detent means is biased is limited by engagement of said struck-out portion with said part of said wall.

27. An electrical conductor terminal receiving means cooperable with one or more plug conductor terminals of the snap type, comprising: detent means, including a plurality of detents each constructed and arranged to cooperate with at least one conductor terminal; at least one of said detents having a generally U-shaped body formed of sheet metal; supporting means so constructed and arranged that it movably supports said detent means and leaves spaces for insertion of conductor terminals into cooperating relation with said detents respectively; said detent means being so pre-constructed and arranged that the inside of the bight of said U-shaped body is left free for insertion of a conductor terminal therein; means for resiliently biasing said detent means to a position to engage and resiliently hold conductor terminals; and said detent means and said biasing means being so constructed and arranged that any selected one or more of said detents is adapted to engage and resiliently hold a conductor terminal, inserted into the selected one or more of said spaces respectively, while any remaining of said spaces are left free for insertion of additional conductor terminals.

28. An electrical conductor terminal receiving means cooperable with a plurality of conductor terminals, comprising: detent means, including a plurality of detents, constructed and arranged to cooperate with the conductor terminals; at least one of said detents having a generally U-shaped body formed of sheet metal; and means for movably supporting said detent means; said supporting means having an aperture a margin of

which registers approximately with the surface defining the inside of the bight of said U-shaped sheet metal body thereby to leave said aperture and said bight free for the insertion of one of the conductor terminals through said aperture and within said inside surface, another of said detents being constructed and arranged to cooperate with said bight and the conductor terminal inserted therein; and means biasing said detents to cooperating position.

29. An electrical conductor terminal receiving means cooperable with a plurality of plug conductor terminals, comprising: detent means, including a plurality of detents, a first one of which has a generally U-shaped body formed of sheet metal, said detent means being constructed and arranged to cooperate with the conductor terminals; a second one of said detents being so constructed and arranged that it is adapted to press a conductor terminal against the inside of the bight of the U-shaped sheet metal body of said first detent; supporting means so constructed and arranged that it movably supports said detent means and leaves spaces for insertion of conductor terminals into cooperating relation with said detents respectively; means for resiliently biasing said detent means to a position to engage and resiliently hold conductor terminals; and said detent means and said biasing means being so constructed and arranged that any selected one or more of said detents is adapted to engage and resiliently hold a conductor terminal, inserted into the selected one or more of said spaces respectively, while any remaining of said spaces are left free for insertion of additional conductor terminals.

HARRY A. DOUGLAS.
